UNITED STATES PATENT OFFICE.

EDWARD H. SAXTON, OF CLEVELAND, OHIO.

BURIAL-CASKET.

SPECIFICATION forming part of Letters Patent No. 430,440, dated June 17, 1890.

Application filed April 3, 1890. Serial No. 346,412. (No model.)

To all whom it may concern:

Be it known that I, EDWARD H. SAXTON, of Cleveland, in the county of Cuyahoga and State of Ohio, have invented certain new and 5 useful Improvements in Burial-Caskets; and I do hereby declare the following to be a full, clear, and exact description of the invention, such as will enable others skilled in the art to which it pertains to make and use the same.

10 My invention relates to improvements in burial-caskets in which is provided a folding shelf and a pocket inside the outer walls of the casket for receiving such shelf, means being provided for holding the shelf in a 15 horizontal position projecting outward from the casket for supporting flowers or other tributes.

In the accompanying drawings, Figure 1 is a side elevation of a burial-casket embodying my invention and showing the shelf extended. Fig. 2 is an enlarged elevation in section. Fig. 3 is an enlarged plan taken below the cover of the casket. Fig. 4 is an elevation in section showing a modification.

25 A represents the body of the casket, and B the cover thereof, and A' one of the end walls of the casket. Just inside of wall A' is an inner wall or partition A², the two walls A' A² inclosing a pocket A³ between them, 30 this pocket being adapted to receive shelf C in the position shown in dotted lines, Fig. 2. This shelf may be of very thin sheet metal, in which case it should be re-enforced—for instance, at or near the edges thereof— 35 by thin metal bars or scraps C' for stiffening the shelf. When the shelf is distended, as shown in Fig. 1 and in solid lines, Fig. 2, shelf C or the attachments thereof rest upon the end wall A', the latter being usually cut 40 away to receive the straps C' flush on top. Straps C' may have hook ends c, adapted to engage, for instance, rod a or other stop or stops. Rod a may be blocked slightly away from wall A², and may then be secured to 45 the latter by for instance, staples; or, as shown, this rod may be supported at the ends by plates a', the latter being permanently secured at the ends of the pocket. The shelf is usually covered with the same kind of fab-

50 ric that covers the casket.

C² is merely a thumb-strap for drawing

the shelf out of the pocket. The stop or fastening device for holding the shelf in a horizontal position may be varied indefinitely without departing from the purpose and spirit 55 of my invention. For instance, in the modification shown in Fig. 4 the shelf is of sheet metal of sufficient thickness to support itself without re-enforcing strips. In such case the inner end of the shelf may be bent hook-shaped, as shown at c', to engage, for instance, hook D of plate D', the latter being secured to partition A². For convenience in attaching the lining or upholstering E, wall A² is preferably of wood; but this wall may 60 be quite thin—say a quarter or three-eighths of an inch (more or less) in thickness—and the pocket and wall A² need not occupy but little, if any, more than an inch lengthwise of the casket, where there is usually ample room 70 in the casket. In case of a thicker shelf (shown in Fig. 4) the end wall A' should be cut away, say, a sixteenth of an inch, or whatever the thickness of the shelf may be, so as to bring the top of the shelf flush with the 75 body of the casket, whereby, in case the casket-cover is provided with hook-fastenings, the cover may be closed down when the shelf is in its extended position. The casket-cover usually projects more or less beyond 80 the body of the casket, and hence the slight crack where the shelf protruded is not noticeable when the shelf is returned to the pocket. If preferred, my improved shelf and attachment may be provided for each end of 85 the casket, or the shelves and pockets could be arranged on the sides of the casket, if called for; and it will be observed that such shelf or shelves do not in the least interfere with attaching handles at the end of the 90 casket or elsewhere.

What I claim is—

1. The combination, with a burial-casket, of a shelf and a pocket constructed inside of the casket, such pocket being adapted to receive such shelf, suitable means being provided for holding the shelf in a horizontal position extending outward from the casket, substantially as set forth.

2. The combination, with a burial-casket 100 having exterior and interior walls inclosing a pocket, of a shelf adapted to enter such

pocket, such shelf being adapted to be extended outward from the casket in a horizontal position, and a stop for engaging the inner end of the shelf or its attachments for holding the shelf distended, substantially as set forth.

In testimony whereof I sign this specifica-

tion, in the presence of two witnesses, this 7th day of March, 1890.

EDWARD H. SAXTON.
